UNITED STATES PATENT OFFICE.

JOHN E. DONOVAN, OF CINCINNATI, OHIO.

PULLEY-MOLDING MACHINE.

SPECIFICATION forming part of Letters Patent No. 593,645, dated November 16, 1897.

Application filed April 17, 1895. Serial No. 546,162. (No model.)

To all whom it may concern:

Be it known that I, JOHN E. DONOVAN, a citizen of the United States, and a resident of Cincinnati, in the county of Hamilton and State of Ohio, have invented certain new and useful Improvements in Pulley-Molding Machines, of which the following is a specification.

My invention relates to machines for molding pulleys. Its object is to provide a machine to rapidly and accurately form molds for pulleys of different sizes, different widths of rim and length of hub, as may be desired. These objects I attain by the means illustrated in the accompanying drawings, in connection with which the invention will be first fully described, and then particularly referred to and pointed out in the claims.

Referring to the drawings, in which like parts are indicated by similar reference-letters wherever they occur throughout the various views, Figure 1 is a vertical diametrical section of my improved machine with the hub and rim patterns in the elevated position for molding a pulley the hub of which is equal in length to the width of the pulley-face, this view being taken through line $z z$ of Fig. 4. Fig. 2 is a detailed view illustrating the means for connecting the rim and hub followers. Fig. 3 is a detailed view of the means for vertically adjusting the hub-pattern with relation to the rim. Fig. 4 is a view, partly in plan and partly in transverse section, taken through line $x x$ of Fig. 1, some portions of the plan view being broken away to expose the parts below and the rim of the top severed by the section-line removed. Fig. 5 is a detailed view of the gearing by which the rim and the hub followers are simultaneously elevated and lowered. Fig. 6 is a view in side elevation of the machine with one of the supporting-columns omitted and some of the fixed parts broken away to more clearly expose the means for adjusting the hub-follower. In this view the hub and rim patterns occupy their lowest positions, as when withdrawn from the mold.

The stationary frame of the machine consists of the base A , the central tubular column A' , the outer upright box-columns A^2 , secured thereon, and the outer rim of the table or follower-board B , secured upon the columns A^2 .

The base for lightness is molded with a circular chamber a surrounding a central tubular portion a' , which projects slightly above the foundation which supports the central column and outer uprights, and the foundation has also an annular depression extending from the base of the central column to the bases of the upright columns, the purpose of which is to lessen machine-work in dressing off the upper surface of the base to seat the central and outer columns. The ends of the central and outer columns are also dressed off true, as is also the under surface of the annular rim B , to form close-fitting joints, so that when the parts are fitted together they are practically as rigid as if cast integral or in a single piece.

The center column A' has an outwardly-projecting flange which is bolted to the base, and the inner circumference of the column also fits around the upwardly-projecting flange of the central portion a' of the base. The bases of the uprights A^2 have also outwardly-projecting perforated flanges a^2 to receive the screw-bolts by which the columns are fastened to the base, and the upper rim B is screwed or bolted securely to the upper webs or flanges of the columns A^2 . The top or follower-board of the table, inside of the rim B , is formed of a series of annular rings, the outer one, b , resting in an annular recess or rabbet in the rim B . The disk or ring b' immediately within this one rests with its inner edge upon top of the column A' , leaving a space between the two to receive the half-rim pattern C . The disk or ring b^2 within this one also rests on the column A' , and its inner diameter has an inwardly-projecting annular flange b^3 , upon which is seated the inner ring b^4 of the follower-board, through which ring the hub-pattern D slides.

Within each of the upright columns A^2 , of which there are four, as shown, is fitted to revolve a screw-shaft E , upon which shafts are nuts E' . These nuts have inwardly-projecting brackets terminating in annular webs c , which are secured by bolts or other suitable means to the rim-follower F , which is fitted to slide vertically outside the column A' . Upon the upper ends of the shafts E are secured pinions E^2 , which mesh with the annular rack G , which is seated in an offset in the

inner and downwardly-projecting flange of the outer rim B and held in place by a ring g, which is secured to the bottom edge of the inner flange of rim B.

5 One of the uprights A² has projecting from it a tubular boss or bearing a³, within which is journaled a crank-shaft H, upon the inner end of which is secured a bevel-gear h, which meshes with a bevel-gear h' upon a vertical 10 shaft h², which has its bearings in the upper flange of the upright A² and the bracket a⁴, which projects inwardly from the outer wall of the column. Upon this same shaft h² is also secured a pinion h³, which meshes with 15 the annular rack G. By placing a crank upon the angular end of the crank-shaft H and revolving it motion is imparted to the annular rack G and through it to the screw-shafts E. By this means the rim-follower F is elevated 20 or lowered as the crank-shaft is turned in one or the other direction and the rim-pattern C elevated to the position shown in Fig. 1, or retracted after the mold is formed, as shown in Fig. 6.

25 The tubular hub-carrier I is fitted to slide within a hub J, which has outwardly-projecting arms j, which project through vertical slots in the central column A'. The ends of the arms are secured to the downwardly-projecting inner flange f of the rim-carrier, in order that the hub J and the rim-carrier will move up and down simultaneously when the rim-carrier is actuated by the gearing set in motion by the crank-shaft H, before described.

30 35 The hub-carrier I is formed with an inwardly-projecting rib i, which is exteriorly slotted to seat a rack I', which is secured within the slot by screw-bolts or other suitable means, and the hub J has projecting 40 from it a perforated boss j' to furnish the inner bearing for the shaft K, upon the inner end of which is secured a pinion k, which engages the teeth of the rack I' for the purpose of adjusting the hub-carrier up and 45 down within the hub J. The outer end of the shaft K has its bearing in a hanger K', which is secured to the rim-follower F. The outer end of the hanger has a circular disk k', the face of which is planed off true to engage a similar disk k², which projects from the 50 hub of the hand-wheel K², which is splined upon the outer end of the shaft K, so that it may have longitudinal motion upon said shaft.

55 The outer end of the shaft K is screw-threaded to receive the screw-threaded hand-wheel K³, by which the friction-surfaces of the disks k' and k² are locked together or released. In order to adjust the hub-pattern relative to the rim-pattern, the screw-nut K³ 60 is turned back, the shaft K revolved in either direction until the hub-pattern is brought to the proper relative position with the rim-pattern, when the nut K³ is again tightened up, locking the hub-carrier rigidly to the hub J.

65 65 The upper ends of the screw-shafts E have their bearings in the inwardly-projecting upper webs of the columns A². The lower ends

of these shafts are turned down, as clearly shown upon the right-hand side of Fig. 1, to pass through halved boxes e, flanged boxes e', and steps e², the latter of which are secured rigidly upon the base of columns A². Within the box e' is a steel disk having a V-shaped annular groove around it to receive the ball-bearings e³, which rest upon a steel washer e⁴, supported upon the step e². The halved boxes e are clamped rigidly upon the reduced end of the screw-shafts by bolts passing through their outwardly-projecting lugs, and the flanged boxes e' are also secured to the shaft 70 by set-screws e⁵. The purpose of this arrangement is to reduce friction, and the downwardly-projecting flange of the box e' prevents dust or sand from getting into the ball-bearings. 75

80 The upper end of the shaft E is axially perforated, the perforations registering with a hole in the rim B, which is stopped by a screw-plug e⁶. There are also transverse perforations in the screw-shaft registering with the axial perforations. The purpose of this arrangement is to lubricate the screw and nut, which is done by removing the plugs e⁶. The outer rim B has also a downwardly-extending flange b⁵ for strength and also to prevent sand and other material working underneath and into the gearing. The interior rings of the follower-board have notches to receive registering keys in order to hold the parts in proper position, so that the divided 90 arm-patterns M and the root of the arm-patterns M' may always register truly with each other when the rim and arm patterns are changed. 95

100 The hub-pattern D is a plain hollow cylinder, in the lower end of which is secured a bottom d, the upper end being closed by a flanged cap d'. The upper cap has a central tube d² extending down from it to receive the core d³, which forms the bore of the hub. 110 The lower fixed bottom d of the hub has a screw-threaded central extension to enter a tapped perforation in the top of the hub-carrier I, by which the hub-pattern is held firmly in place. The core d³ is supported upon a 115 rod d⁶, the lower end of which is secured in the hub of the spider d', the arms of which spider are secured to the flange surrounding the central base-opening a'. The rod d⁶ extends through a central perforation in the 120 bottom d of the hub-pattern. The upper end of rod d⁶ is provided with a removable cap d⁸ to form a seat for the core. The core, which is baked, slips freely through the downward extension d², and after the mold is formed 125 and the flask removed the core will be lifted with the sand mold, in which it is firmly embedded.

130 The purpose of adjusting the bottom end of the core slightly below the level of the follower-board is to insure a close fit of the two half-cores when the flasks are put together, the weight of the cope pressing one or other of the half-core patterns slightly into the sand.

To mold pulleys of different-sized bores, it is only necessary to change the upper cap d' and substitute another one with a larger or smaller central tube, as d^2 .

5 Upon one side of the hub-pattern is adjustably secured, as shown in Fig. 1, the boss-pattern d^3 by a screw or pin passing through a perforation in its upper end and into the wall of the hub-pattern. This boss-pattern 10 is used when tight pulleys that require set-screws to hold them in position are to be molded.

When a pulley-hub requiring no boss is to be molded, the pin in the upper end of the 15 boss-pattern is removed and the pattern dropped down on a level with the top of fillet or ring m , which forms the edge finish of the root-piece of the arms M' . The root M' of the arms is secured upon the inner ring b^4 of the 20 follower-board, and the purpose of the collar or fillet m , which is removably fitted between the hub-pattern and root of the arms, is to enable me to place different diameters of hub-patterns with the same or different 25 rim-pattern. If the hub-pattern is required to be of a greater or less diameter, a wider or narrower fillet or ring is employed. The root of the arms M' is removably secured upon the central ring b^4 of the follower- 30 board by dowel-pins which enter holes in the ring, and the outer portions of the arms M are secured upon the ring b^2 by dowel-pins projecting from the under side of said arms. The arm-patterns and the root of the arms 35 are preferably formed hollow on the under side, so that the edges may fit snugly down upon the follower-board, to which they are removably secured by the pins, so that the different sizes or lengths of arms may be interchangeably used for molding different 40 kinds of pulleys. The central ring b^4 has also pins projecting down from it to enter holes in the inwardly-projecting flange b^3 , which insures the proper registration of the 45 root with the outer portion of the pulley and arm patterns.

It will be seen that by changing the different removable rings of the follower-board the same machine may be readily adjusted 50 to mold many different diameters of pulleys. The width of the pulley-rim and length of hub may also be varied within considerable range by the means for actuating the rim and hub carriers.

55 The set-pins N for the half-flasks have a reduced tenon to enter holes in the table and a cylindrical portion n , projecting above the table, to accurately seat the half-flasks upon the table, while the portion above the cylindrical portion is cone-shaped to guide the pins to their seats.

I have shown in the drawings and described my invention as relating particularly to belt-pulleys, but it is obvious that a pattern for toothed gear-wheels may be substituted in place of the rim-pattern, the opening in the follower-board being formed to per-

mit the elevation or depression of a cogged rim instead of a plain one.

The construction set forth has been found 70 eminently successful in practice and free from those defects so common in machines of this class incident to lack of rigidity and protection of parts. Accurate mechanism working in molding-sand is working under 75 the most unfavorable conditions, and failure in mechanism of an otherwise high character has resulted in machines of this class by reason of accuracy of adjustment and movement being defeated by the presence of sand 80 in undesired places. One of the unfortunate conditions obtaining with molding-machines is that the mechanism from which accurate results are desired must be located below the sand being dealt with. In my system of 85 construction I combine rigidity with the perfection of protection of mechanism and accuracy of adjustment of movement.

The requirement of the present pulley art is for what may be called "blended junctures" or the avoidance of angles where arms join each other or join the rim or the hub. In outfitting a pulley-molding machine a satisfactory result can be arrived at by making the arm-pattern complete, as a spider accurately filleted at the hub; but this would be enormously expensive owing to the variety of relative hub sizes and arm sizes called for by the market. Hence the distinct advantage of making the major portion of the arms as 95 separate individual patterns. The roots of the arms has a separate single spider-like structure, and the fillet at the hub has a separate ring fitting within the arm-root pattern and fitting around the hub, each member being thus independently changeable. These 100 sectional arm-patterns in my construction find their support on the sectional follower-board described, one section of follower-board carrying the arm-root pattern and the fillet-pattern, while the next outer section of the follower-board unites and carries the 105 separate arm-patterns, which also find support upon the next outer section of the follower-board. By this plan of construction a 110 standardized system of arm-patterns can be permanently mounted, each side upon a follower-board section, the set being put into the machine when desired. Similarly, follower-board sections may be provided with 115 standardized arm-root patterns adapted to receive various fillet-patterns to suit various 120 standardized sizes of hubs. Under this system there may be produced, with a limited and economical system of patterns, a vast variety of accurately-molded and beautiful pulleys varying in size of rim, in section of arms, in number of arms, in size of hub, and character of arm-root, all of the junctures nicely 125 blending.

130 It is also obvious that many mere mechanical changes may be made in the machine without departing from the spirit or scope of my invention, and hence

Without limiting myself to the precise details shown, what I claim as new, and desire to secure by Letters Patent, is—

1. In a pulley-molding machine, the combination, substantially as set forth, of a frame, an annular outer table-rim rigidly supported thereby and forming the margin of the follower-board, follower-board sections disposed within and on the plane of said table-rim, a rim-pattern arranged to slide vertically in the follower-board, a rim-carrier secured to the lower part of the rim-pattern below the follower-board, nuts secured to said carrier and projecting outwardly under said table-rim, vertical screw-shafts journaled in fixed bearings in the frame under said table-rim and engaging said nuts, pinions fast on the upper ends of said screw-shafts under said table-rim, an annular rack mounted in a bearing under said table-rim and engaging said pinions, and gearing mounted on the frame and engaging said annular rack and serving in turning said rack by hand.
2. In a pulley-molding machine, the combination, substantially as set forth, of a frame, an annular outer table-rim rigidly supported thereby and forming the margin of the follower-board, follower-board sections disposed within and on the plane of said table-rim, a rim-pattern arranged to slide vertically in the follower-board, a rim-carrier secured to the lower part of the rim-pattern below the follower-board, nuts secured to said carrier and projecting outwardly under said table-rim, vertical screw-shafts journaled in fixed bearings in the frame under said table-rim and engaging said nuts, pinions fast on the upper ends of said screw-shafts under said table-rim, an annular rack mounted in a bearing under said table-rim and engaging said pinions, gearing mounted on the frame and engaging said annular rack and serving in turning said rack by hand, a hub or cylinder disposed centrally below the follower-board and rigidly united with said rim-carrier, a hub-carrier arranged to slide vertically in said hub or cylinder, a hub-pattern carried by said hub-carrier and projecting upwardly through the follower-board, and means for vertically adjusting said hub-carrier in said hub or cylinder.
3. In a pulley-molding machine, the combination, substantially as set forth, of a frame, an annular outer table-rim rigidly supported thereby and forming the margin of the follower-board, follower-board sections disposed within and on the plane of said table-rim, a rim-pattern arranged to slide vertically in the follower-board, a rim-carrier secured to the lower part of the rim-pattern below the follower-board, nuts secured to said carrier and projecting outwardly under said table-rim, vertical screw-shafts journaled in fixed bearings in the frame under said table-rim and engaging said nuts, pinions fast on the upper ends of said screw-shafts under said table-rim, an annular rack mounted in a bearing

under said table-rim and engaging said pinions, gearing mounted on the frame and engaging said annular rack and serving in turning said rack by hand, a slotted cylindrical column disposed below the follower-board and forming a vertical guide for said rim-carrier and a support for sections of the follower-board, a hub or cylinder disposed within said column and having arms projecting outwardly through the slots thereof into rigid engagement with said rim-carrier, a hub-carrier fitted to slide vertically in said hub or cylinder, means for adjusting and locking said hub-carrier in said hub or cylinder, a hub-pattern carried by said hub-carrier and projecting upwardly through said follower-board, and removable follower-board sections supported by said column and encircling said hub-pattern.

4. The combination of the frame, the sectional follower-board through which the hub and rim patterns slide, a central support for the inner sections of the follower-board, the rim-pattern carrier, a guide for the hub-pattern carrier secured to the carrier for the rim-pattern, said guide and rim-carrier being provided with shaft-bearings, the transverse shaft fitted to revolve in said bearings, a pinion secured upon the inner end of said shaft, the hub-pattern carrier fitted within said central guide, a rack secured to the said carrier to mesh with the pinion upon the transverse shaft, a hand-wheel upon the end of the shaft to revolve the same for the purpose of actuating the hub-pattern carrier independently of the rim-carrier, and means such as shown to lock the hub-carrier, its guide and the rim-carrier together, substantially as shown and described.

5. In a pulley-molding machine, the combination, substantially as set forth, of a frame, a sectional follower-board supported thereon, rim and hub patterns adapted to slide through said sectional follower-board, carriers for said patterns rigidly connected together below said follower-board, vertical screw-shafts disposed below said follower-board and journaled at their upper ends in bearings in the top of said frame and at their lower ends in antifriction-bearings at the base of said frame, nuts engaging said screw-shafts and rigidly connected with said carriers, pinions fast upon the upper ends of said screw-shafts, an annular rack engaging said pinions and journaled in an annular bearing supported by said frame, and gearing connected with said annular rack to serve in turning said rack by hand.

6. In a pulley-molding machine, the combination, substantially as set forth, of a sectional follower-board, arm-patterns on an intermediate section thereof, a hub-pattern sliding through the central portion of the follower-board, an arm-root pattern secured to said central section of the follower-board around the hub and common to all of the arm-patterns, and a removable fillet-pattern

ring fitting around the exterior of the hub-pattern and within the interior of said arm-root pattern and supported directly by said central follower-board section.

5 7. The hub-pattern, consisting of a hollow cylinder, and a removable cap therefor having a downwardly-extending central tube to receive a core for forming the bore of the hub, substantially as shown and described.

10 8. The combination, in a pulley-molding machine, of the sectional follower-board, the hub and rim patterns adapted to slide therethrough, followers for the said hub and rim

patterns, means for elevating and lowering said followers with their patterns secured thereon, the hub-pattern having a central tubular portion to receive a core for forming the bore of the hub, and the central support passing through the base of the hub pattern and follower to support said core, substantially as shown and described. 15 20
